HELMET

Stephen V. Grancsay, New York, N. Y., and Russell W. Ehlers, Silver Spring, Md., assignors to the United States of America as represented by the Secretary of the Army

Application January 22, 1952, Serial No. 18,152

Term of patent 14 years

(Cl. D3—13)

To all whom it may concern:

Be it known that we, Stephen V. Grancsay and Russell W. Ehlers, both citizens of the United States, residing, respectively, at New York city, in the county of Queens and State of New York, and at Silver Spring, in the county of Montgomery and State of Maryland, have invented a new, original, and ornamental Design for a Helmet, of which the following is a specification, reference being had to the accompanying drawings, forming a part thereof.

Figure 1 is a side perspective view of a helmet showing our new design.

Figure 2 is a front elevational view thereof,

Figure 3 is a top plan view, and,

Figure 4 is an elevational view of the side opposite to that shown in Figure 1.

We claim:

The ornamental design for a helmet, substantially as shown.

STEPHEN V. GRANCSAY.
RUSSELL W. EHLERS.
